UNITED STATES PATENT OFFICE.

LOWE E. SIMPSON, OF CINCINNATI, OHIO, ASSIGNOR OF ONE-HALF TO ORVILLE SIMPSON, OF CINCINNATI, OHIO.

GAS-ENGINE.

1,201,107.

Specification of Letters Patent.

Patented Oct. 10, 1916.

Application filed September 4, 1913. Serial No. 788,040.

To all whom it may concern:

Be it known that I, LOWE E. SIMPSON, a citizen of the United States, residing at College Hill, Cincinnati, Hamilton county, 5 Ohio, have invented certain new and useful Improvements in Gas-Engines, of which the following is a specification.

The present invention pertains to improvements in internal combustion engines 10 of the four-cycle type and by four-cycle is meant successive strokes representing combustion and power, exhaust, intake of fuel, and compression.

The invention relates particularly to improvements in the valve-system of engines 15 of the before-mentioned well known type.

While my improvements are applicable to single or multiple-cylinder engines I have thought best to illustrate the improvements 20 as exemplified in a single cylinder engine. The improvements are applicable to gas engines with their cylinders vertical or horizontal or diagonal or to engines with their cylinders above or below the crank-shaft. 25 I have illustrated my improvements as embodied in a vertical engine having its cylinder disposed above its crank-shaft, and it is therefore to be understood that the expressions above and below and up and down 30 are to be considered in the relative sense. The engine is illustrated as having its crank-shaft running in counter-clockwise direction.

The improvements will be readily understood from the following description taken 35 in connection with the accompanying drawings in which:—

Figure 1 is a vertical section of a gas engine exemplifying my improvements, the 40 section being in the diametrical plane of the working-cylinder and valve-cylinder: Figs. 2 to 10, inclusive, diagrammatic illustrations of the valve-system: Fig. 11 a dia- 45 grammatic side elevation of the valve-sys- tem: and Fig. 12 a horizontal section, in the plane of line *a* of Figs. 10 and 11, of the valve parts.

In the drawings: 1, indicates the cylinder 50 of the engine: 2, the crank-case: 3, the crank-shaft: 4, the crank-pin: 5, the circular path of the crank-pin: 6, the piston: and 7, the connecting-rod, the parts thus far referred to not essentially presenting any peculiarities of structure: 8, indicates the valve-cas- 55 ing, which is illustrated as being cylindrical

in cross-section and with its axis disposed nearly parallel with the axis of the cylinder: 9, a fuel inlet for the valve-case: 10, an annular series of ports leading from the fuel-inlet to the interior of the valve-casing: 11, an exhaust-outlet from the valve-casing: 12, an annular series of ports leading from the valve-casing to the exhaust outlet: 13, a bushing fixed within the valve-casing and having through it the ports 10 and 12: 14, the combustion chamber: 15, the cylinder-head, serving also as the head for the valve-casing: 16, the passage placing the upper end of the valve-casing in communication with the combustion-chamber: 17, water-jacketing: 18, a sleeve-valve coöperating with the bushing of the valve-casing as a seat: 19, a circular series of fuel inlet-ports leading through the wall of the sleeve-valve from fuel-inlet-ports 10 to the interior of the sleeve-valve: 20, a piston-valve working within the sleeve-valve: 21, a valve-operating crank-shaft: 22, a sprocket-wheel thereon: 23, a sprocket-wheel on the engine crank-shaft, this sprocket-wheel being half the diameter of sprocket-wheel 22: 24, a chain connecting the two sprocket-wheels: 25, a crank-pin of the valve-operating crank 21: 26, a fixed pivot disposed below the valve-operating crank-shaft: 27, a link connected with this pivot: 28, a pivot at the upper end of link 27: 29, a bell-crank pivoted on the crank-pin 25 and having its lower arm connected with pivot 28: 30, a pivot carried by the upper arm of the bell-crank: 31, a link connecting pivot 30 of the bell-crank with the piston-valve: 32, a link connecting pivot 28 of the bell-crank with the sleeve-valve: 33, the substantially elliptical path of pivot 30: 34, the curved path 95 of pivot 28: and 35, the circular path of crank-pin 25.

The regimen of the valve-system will be best understood from the diagrams of Figs. 2 to 10 inclusive, it being understood that Figs. 1 and 2 correspond with each other in position of parts and that Figs. 10 and 11 correspond with each other in position of parts. Assume that the engine crank is turning in counter-clockwise direction as illustrated, and assume that the zero of crank position is at the top of the crank-pin circle, corresponding with the uppermost position of the engine-piston, and understand that the stated degrees of position for 100 105 110

the engine crank-pin are approximate. Fig. 2 shows the ignition position of the valve-parts, the inlet and exhaust ports being closed, corresponding with the engine crank-pin being in the 350° position. Fig. 3 shows the valve-parts when the engine crank-pin is in 90° position, inlet and exhaust ports still being closed, the expansion of the burning gases forcing the engine-piston downward, the pressure of the burning gases on the piston-valve and sleeve-valve tending to supplement the power of the main piston notwithstanding the piston-valve and the sleeve-valve are normally driven by the main piston. In Fig. 4 the exhaust is starting to open by the downward movement of the sleeve-valve coöperating with exhaust-ports 12, the engine crank-pin having reached the 160° position and the power stroke of the engine being nearly completed. In Fig. 5 the exhaust-ports have been fully opened by the downward movement of the sleeve-valve, corresponding with the 270° position of the engine crank-pin and the halfway up position of the engine piston on the exhaust stroke. In Fig. 6 the sleeve-valve has reversed its direction of motion and has gone up and just closed the exhaust ports, the engine crank-pin having passed its upper center and reached its 10° position. In Fig. 7 the upper end of the sleeve-valve is on lap, the inlet-ports through the sleeve-valve are partially opened at the upper end of the piston valve and the inlet-ports 19 in the sleeve-valve are just beginning to open from inlet-ports 10, corresponding with the 20° position of the engine crank-pin and the initiation of the suction-stroke of the engine. In Fig. 8 the sleeve-valve is in increased lapping relationship with the exhaust ports and, notwithstanding both valves are rising, the inlet-ports are full open, corresponding with the 105° position of the engine crank-pin. In Fig. 9 the inlet-ports through the sleeve-valve have just been closed by the superior rising of the piston-valve, corresponding with the 195° position of the engine crank-pin, or 15° past its lower dead center. In Fig. 10 all ports are closed, corresponding with the 270° position of the engine crank-pin, and with the halfway up compression position of the engine piston, the rising of the piston-valve assisting the compression.

It will of course be understood that the timing of the valve-parts is to be varied in engines of different sizes in order to secure the best results, heavy parts and slow speed requiring different timing from engines of light weight and high speed, and it will also be understood that the relative positions of the axes of the valve-casing and working cylinders may be varied, according to design, and that the piston-valve and sleeve-valve supplement each other and that

the cylindrical form of these parts is incident to the cylindrical type of valve illustrated. While it may not be proper to designate either of the two valve-members as the primary member, regardless of whether the valve-members are of the cylindrical type or otherwise, I will, in the claims, designate the valve-member typified by the valve-sleeve as the first valve-member, and I will designate the valve-member typified by the piston-valve as the second valve-member.

My improved system will lend itself to many variations in construction, a single exemplification only having been set forth. I have sought simply to explain the principle of my invention and to set forth the best mode in which I at present contemplate embodying that principle.

I claim:

1. A four-cycle gas-engine comprising, a valve-casing having one end constantly in communication with the combustion-chamber of the engine and provided with a series of fuel inlet-ports and provided with a parallel series of exhaust-ports nearer said combustion-chamber, a first valve-member working in said valve-casing and adapted to have its end coöperate with the before-mentioned exhaust-ports and provided with a series of inlet-ports to coöperate with the first-mentioned inlet-ports, a second valve-member having its end adapted to coöperate with the inlet-ports of the first valve-member, a valve-moving crank, mechanism for transmitting rotation to said crank from and at half the speed of the engine-shaft, a fixed pivot, a link connected with said fixed pivot, a bellcrank mounted on the pin of said crank and having one arm pivoted to said link, a link connecting the other arm of the bellcrank with the second valve-member and a link connecting the first-mentioned link with the first valve-member, combined substantially as set forth.

2. A four-cycle gas-engine comprising, a main cylinder, a cylindrical valve-casing having one of its ends in constant communication with the combustion chamber of the main cylinder and provided with an annular series of fuel inlet-ports and with an annular series of exhaust-ports nearer said combustion chamber, a sleeve-valve working in said valve-casing and provided with an annular series of inlet-ports to coöperate with the inlet-ports of the valve-casing and having its end adapted to coöperate with the exhaust-ports of the valve-casing, a piston-valve working within the sleeve-valve and having its end adapted to coöperate with the inlet-ports of the sleeve-valve, a valve-moving crank, mechanism adapted to transmit motion to the valve moving crank from and at half the speed of the engine-shaft, a bellcrank mounted on the pin of the valve-moving crank, a link pivotally con-

necting one arm of the bellcrank with the piston-valve, a fixed pivot, a link connected to the fixed pivot and pivoted to the other arm of the bellcrank, and a link pivotally connecting the sleeve-valve with the second arm of the bellcrank, combined substantially at set forth.

3. In a gas engine, the combination of a combustion chamber, a main cylinder, a valve cylinder, a crank shaft, a main piston in the main cylinder connected with the crank shaft, two valve pistons in the valve cylinder, connecting rods, one pivoted to each of the valve pistons, and driving means actuated by the crank shaft and connected to the lower ends of the valve connecting rods, said driving means being constructed and arranged to cause the lower end of one of the valve connecting rods to move substantially in an elliptical path and the other to move substantially in a short arcuate path.

4. In a gas engine, the combination of a combustion chamber, a main cylinder communicating therewith, a valve cylinder communicating with the combustion chamber at one end and provided with an inlet port and an exhaust port at different points of its length, a sleeve moving in said valve cylinder having its bore open toward the combustion chamber and having its end adapted to open and close said exhaust port and a valve piston working within said sleeve, the sleeve being provided with a port coöperating with said piston to open and close communication between said inlet port and the cylinder through the valve sleeve, a main piston in said main cylinder, a crank shaft connected therewith, an eccentric member driven from the crank shaft at half speed, a substantially triangular member pivoted on said eccentric at one apex, a connecting link pivoted

to said member at another apex and also pivoted to said valve piston, another connecting link pivoted to said triangular member at its third apex and also pivoted to said valve sleeve, and an oscillating link pivoted to said third apex of the triangular member at one end and at the other end pivoted at a fixed point.

5. In a gas engine, the combination of a combustion chamber, a working cylinder, a piston therein, a crank shaft connected to the piston, a valve cylinder communicating with the combustion chamber, two reciprocating valve members therein, a valve operating shaft driven from the crank shaft and valve driving means actuated by the valve shaft for reciprocating the valves to control the intake and exhaust, said means being constructed and arranged to minimize the longitudinal travel of said valve members.

6. In a gas engine, the combination of a combustion chamber, a main cylinder, a piston, a crank shaft connected therewith, a valve chamber communicating with the combustion chamber, two valve members therein, a valve shaft driven from the main shaft and having an eccentric member, a triangular driving member on the eccentric, a pitman connecting one point of the triangular member with one of the valve members, another pitman connecting another point of the triangular member with the other valve member, and a link having at one end a fixed pivot and at the other end connected to the triangular member.

LOWE E. SIMPSON.
